UNITED STATES PATENT OFFICE.

FRED A. NEIDER, OF AUGUSTA, KENTUCKY, ASSIGNOR TO THE F. A. NEIDER COMPANY, OF AUGUSTA, KENTUCKY, A CORPORATION OF KENTUCKY.

VEHICLE CURTAIN-FASTENER.

1,113,677.

Specification of Letters Patent. Patented Oct. 13, 1914.

Application filed September 28, 1910. Serial No. 584,218.

To all whom it may concern:

Be it known that I, FRED A. NEIDER, a citizen of the United States of America, and resident of Augusta, county of Bracken, and 5 State of Kentucky, have invented certain new and useful Improvements in Vehicle Curtain-Fasteners, of which the following is a specification.

My invention relates to vehicle curtain 10 fasteners, of the class in which an elongated head is pivoted upon an elongated base, in a manner such that the longer axis of the head may be brought and held either parallel to or at right angles to the longer axis 15 of the base, so that in the former position, the head may be passed through a button hole in a curtain, and the head may then be turned to the latter position, to hold the curtain in place.

20 The object of my invention is a fastener of the class described, and which is light, ornamental, economical in construction, and strong.

This object is attained by the means de- 25 scribed in the specification, and illustrated in the accompanying drawings, in which,

Figure 1 is a side elevation of a vehicle curtain fastener embodying my invention. Fig. 2 is a plan view of a blank, from 30 which the head and the pivot stem are formed. Fig. 3 is a sectional view taken upon line 3—3 of Fig. 1. Fig. 4 is a longitudinal central sectional view of the base. Fig. 5 is a plan view of the base, with the 35 head shown in its locking position, in dotted lines.

Referring to the parts:—The carriage curtain fastener consists of an integral head A' and pivot stem for swiveling the head 40 upon a base E'. The pivot stem passes through a perforation in the top of the base and engages a washer F, upon the interior of the hollow base, and the head is held in the position to which it is set by 45 means of a coiled spring G, which is located between the washer F and the top of the base E'.

The head A' is formed from a blank of sheet metal, which consists of central strip 50 A, end tags B B', and intermediate strips D D'. Central strip A has converging sides a a' a² and a³ and tapered ends a⁴ a⁵ a⁶ and a⁷. The intermediate strip is rectangular in shape.

55 In forming the head from the blank, it

is bent about its transverse axis, bringing the edge a into contact with the edge a', and the edge a² into contact with the edge a³, and the central part of the blank is drawn outward, to form the rounded top of the head. The tapered ends a⁴ a⁵ a⁶ and a⁷ form the outer corners of the head, the intermediate strips D D' form the conical bottom of the head and the tangs B B' contacting with each other, form the pivot stem of the head, 60 and are turned outward at their lower ends b b', to hold the washer F upon the stem. The bottom of the head is undercut, adjacent to the corners thereof forming square shoulders. The base is struck up from a sheet of metal, into a horizontal plate e and a vertical boss e'. The top of the boss has a longitudinal recess e², which is crossed centrally by a transverse notch e³ leaving a continuous curved ridge around each edge of 70 the boss. The plate e has around its periphery a down-turned flange e⁴ and has screw holes surrounded by down-turned flanges e⁵.

When the fastener is in its inoperative 80 position, viz., in position to be inserted into an eyelet, as shown in Fig. 1, the tapered portion of the bottom formed by the parts D D' are seated in the recess e², and the shoulders of the head rest upon the curved 85 ridges at ends of the top of the boss e'. There is thus no perceptible space left between the base and the head which enhances the ornamental appearance thereof.

When the head is turned to its operative 90 position, viz., at right angles to the position shown in Fig. 1, the tapered portion of the bottom rests in the notch e³, and the abrupt shoulders of the head form a square contact 95 against which the outer face of the curtain bears firmly, thus preventing the fastener slipping through the eyelet. By having an open space left in the bottom of the head, and by forming undercut shoulders, additional space is left between the plate e and 100 the head, to provide room for thick curtains.

What I claim is:—

1. A vehicle curtain fastener comprising a base having an elongated boss formed thereon and provided with a longitudinally extending shoulder-receiving depression in the face thereof, a marginal rib along each end of the face, and a shoulder-receiving depression extending transversely across the face thereof and between the ribs at a point 105 110

intermediate the ends of the boss, an elongated head pivotally secured to the boss and located axially, with relation thereto, and having shoulders formed thereon intermediate the ends thereof, for engaging the transversely extending depressions when the head is turned to an operative position, with relation to the boss, and for projecting into the longitudinally extending depression when the head is turned to an inoperative position, with relation to the boss, said shoulders being of such altitude, with relation to the depth of the longitudinally extending depression, that the head rests upon the marginal ribs when the boss is in the inoperative position, and means for holding the head against the face of the boss.

2. A vehicle curtain fastener comprising a base, an elongated boss formed on the base and having longitudinal and transverse depressions formed therein, marginal ribs surrounding the ends of said longitudinal depression, an elongated head formed of sheet metal and conforming to the outline of said boss and pivotally mounted on said boss, means for yieldingly pivoting said head on said boss, strips formed integrally with the metal of said head and brought together at their lower edges to form shoulders adapted to engage said longitudinal or transverse depressions, and tangs formed on said strips, adapted to engage said boss to form

a pivot for said head and a securing device for said yielding means.

3. A vehicle curtain fastener comprising, a head, oval in cross-section, and having shoulders formed on the inner face and located intermediate the ends thereof, a base having an oval boss formed thereon and provided, in the face of the boss, with a longitudinally extending shoulder-receiving slot, a marginal rib formed on each end of the boss and a transversely extending shoulder-receiving recess located midway between the ends of the boss and between the ribs, and a spindle for pivotally connecting the head in a central position, with relation to the boss and a spring for drawing the head against the face of the boss, said shoulders being so proportioned and located on the head, that they engage the transversely extending recess, when the head is turned to a position at right angles to the boss, and project into the longitudinally extending recess when the head is turned to a position parallel with the boss, and said ribs being so proportioned and located on the boss that each shoulder moves across one rib in passing from one recess to the other.

FRED A. NEIDER.
